Primary Examiner — Selina Sikder

(57) **CLAIM**

The ornamental design for a heat spreader for a VCSEL array and mounting support, as shown and described.

DESCRIPTION

FIG. 1 is a top perspective view of the heat spreader for a VCSEL array and mounting support;

FIG. 2 is a top elevation view thereof;

FIG. 3 is a bottom elevation view thereof;

FIG. 4 is a right side elevation view thereof;

FIG. 5 is a left side elevation view thereof;

FIG. 6 is a front elevation view thereof; and,

FIG. 7 is a rear elevation view thereof.

The broken lines illustrated in the Figures form no part of the claimed design.
